UNITED STATES PATENT OFFICE.

HENRY J. MCKENZIE, OF CLEVELAND, OHIO.

AUTOMATIC GRID-PASTING MACHINE.

Application filed October 28, 1920. Serial No. 420,324.

This invention relates to new and useful improvements in applying or pasting active material upon electric storage battery electrodes or grids, and, principally, to a machine 5 for automatically feeding and applying paste to the grids, thereby eliminating all manual labor for the accomplishment of the functions performed by the machine.

The invention also has for its objects, to apply active material to and to force the same through opposite faces of the grids whereby the active material will be compactly and firmly affixed or adhered to the same; to feed the active material to the means for applying 10 the same to the grids in a manner to be evenly distributed upon said means in order that the active material will be evenly pasted upon the grids to completely fill the designated portions thereof; and to automatically deliver the 15 grids at proper intervals and in the proper positions to be acted upon by the means for pasting the grids, said delivering means including means for conveying the grids to a finishing or smoothing arrangement, whereby 20 all surplus active material will be removed and conducted back to means for mixing the same.

Another object of the invention is to provide means for automatically stopping the 25 active material feeding mechanism when the supply of grids has been exhausted, thereby preventing clogging of the machine and waste of material.

Other objects and advantages of the invention will become apparent during the course of the following description.

In the accompanying drawings, forming a part of the application, embodiments of my invention which are at present preferred are 30 shown, but it is to be understood that I do not desire to limit myself to the construction, arrangement and combination of the various parts herein shown, and that I may resort to various changes in the construction, arrangement and combination of the various parts of the invention to be hereinafter described and set forth in the appended claims.

In the drawings, wherein like numerals are employed to designate like parts throughout 35 the several views—

Figure 1 is an end elevation of the invention.

Figure 2 is a transverse section through the same.

Figures 3 and 4 are fragmentary longitudinal sections through the same. 55

Figures 5 and 6 are fragmentary top plans of the invention.

Figure 7 is an enlarged detail section of a part of the grid pasting mechanism. 60

Figure 8 is an enlarged fragmentary section of a part of the grid pasting mechanism.

Figure 9 is an elevation of a part of the above arrangement.

Figures 10 and 11 are plan and elevation of another part of said arrangements. 65

Figure 12 is a transverse section of one of the active material passage ways.

Figures 13 and 14 are details of other parts of the pasting mechanism. 70

Figure 15 is an end elevation of the feed member.

Figure 16 is a side elevation of the same.

Figure 17 is a side elevation of the grid feeding mechanism. 75

Figure 18 is an end elevation of the same.

Figure 19 is a fragmentary plan of the upper end of the feed mechanism.

Figure 20 is a fragmentary side elevation of a portion of the feed mechanism. 80

Figure 21 is a top plan of the same.

Figures 22 and 23 are details of the feed mechanism.

Figures 24, 25, 26 and 27 are details of the automatic stop mechanism, and 85

Figures 28, 29, 30 and 31 are views of the endless conveyor.

In the manufacture of electric storage battery electrodes, better known as plates, a lead grid or foraminous plate forms the foundation of the electrode. Lead oxide and other ingredients are used in making the active material which is applied or "pasted" upon the grids, the active material before being formed upon the grids being of about the consistency 90 of soft putty. Heretofore in most instances this active material has been applied or pasted upon grids by hand, by means of smearing the active material upon opposite sides of the grid with wooden paddles. The present invention has therefore been designed primarily to apply the active material to the grids by machine, thereby, greatly increasing the output of the electrodes and consequently 95 100.

storage batteries to meet the ever increasing demand for such products.

In the accompanying drawings wherein for the purpose of illustration is shown the 5 preferred embodiment of the invention, I have illustrated a machine of a plural unit type for very high production, but it is of course understood that the machine may be constructed with only one unit in cases where 10 high production is not essential. This invention embodies a mechanism for thoroughly mixing the ingredients for making the active material and consists of a hopper 1 arranged at each end of the machine and connected 15 by a double longitudinally extending track way 2 as most clearly shown in Figures 4 and 5. This track way is of trough shape in cross section, the bottom thereof being provided with apertures for the purpose of permitting 20 the oxide powder, which is conveyed from the hoppers by an endless conveyor 3, to descend into a vibrator 4 arranged therebeneath. The endless conveyor consists of a cable 5 engaged about the special sprockets 25 6, one of which is mounted horizontally in the bottom of each hopper. Each sprocket consists of a plurality of spaced radiating arms 7, as most clearly seen in Figure 5, which arms at their extremities are provided with 30 grooves for the reception of the cable 5 and between each two arms, a shoulder 8 is provided for engagement with the disks 9 secured at intervals along the conveyor cable 5. It will be noted that the edge of each arm adjacent 35 the shoulders is cut away so as to permit of the disks 9 conveying the oxide powder from the hopper 1. Each disk of the conveyor is provided with cut out portions as most clearly seen in Figure 2, so that the oxide 40 powder may be spread along the double track way and forced through the apertures therein.

The vibrator 4 arranged beneath the double track and above the flared mouth of the longitudinally extending mixing chamber 10, consists of an elongated tray, V-shaped in cross section and equipped in its bottom with a longitudinally extending slot, or openings, whereby the oxide powder may drop into the 45 mixing chamber. Opposite ends of the vibrating tray 4 are provided with longitudinally extending outwardly projecting pintles 11 which are adapted for reciprocation in brackets 12 secured to opposite ends of the machine. To one of these pintles is pivotally connected an eccentric rod 13 having its eccentric 14 mounted upon a transversely extending shaft 15 which is mounted in suitable brackets upon the end of the machine. As 50 most clearly seen in Figure 1, one end of this shaft is extended beyond its bearing bracket and is equipped with a sprocket 16 which is rotated by a sprocket chain 17 engaging a similar sprocket 18 upon a stub shaft 19 upon 55 the base of the machine and receiving motion

through the intermediacy of beveled gears 20 and 21, a sprocket 22 and a sprocket chain 23 engaging the last named sprocket, and a sprocket 24 mounted upon a driven shaft 25 extending longitudinally of the machine and 60 journaled in suitable bearings carried by the frame of the machine.

As best seen in Figure 6, the driven shaft 25 is provided with a relatively large gear 26 which meshes with a smaller gear 27 mounted upon a power shaft 28 journaled in bearings at opposite ends of the machine. A clutch 29 is associated with the power shaft, whereby rotation of the driven shaft is controlled at the will of the operator. One 70 end of the power shaft is extended beyond the frame of the machine and equipped with a large gear 30 which is adaptable to operate the invention.

Directly above the driven shaft 25 and extending longitudinally of the machine to be journaled in bearings 31 at the ends of the frame is a conveyor shaft 32 upon which is keyed a Geneva stop or Geneva wheel 33 having four radial equally spaced slots therein. A laterally extending pin 34 carried by a disk 35 keyed to the driven shaft is adapted for cooperation with the Geneva wheel for intermittently operating the same.

Returning to the mixing chamber 10, shafts 36 extending longitudinally through the mixing chamber have opposite ends extended through bearings formed upon the opposite ends of the mixing chamber. These shafts extend in spaced parallel relationship 100 and each is equipped with a plurality of blades or paddles 37 arranged at different angles around their respective shafts, the blades of one shaft being adapted to pass between the blades of the coacting shaft so that 105 the oxide powder falling into the mixing chamber from the vibrator will drop upon the blades and become thoroughly mixed with the liquid ingredients of the active material which enter the top of the mixing chamber 110 through pipes 38 branching from a main supply pipe 39. This main supply pipe is arranged vertically of the machine and enters a pumping mechanism 40 as most clearly shown in Figure 2, arranged on the base of 115 the machine and operated by means of a sprocket chain 41 engaging a sprocket keyed to the driven shaft 25. The extended end of each mixing shaft 36 is provided with a sprocket 42 and one of the shafts is equipped 120 with an additional sprocket 43 for engagement with a sprocket chain 44 leading from a sprocket 45 keyed to the driven shaft. A sprocket chain 46 engages sprockets 42 whereby the blades of the mixing shafts 36 are rotated in a manner that they will move inwardly toward each other as clearly shown 125 by the arrows in Figure 2.

The special sprockets 6 within the hoppers 1 receive rotation from one of the sprockets 130

being secured to a vertical shaft 47 having its lower end equipped with a worm gear 48 adapted for meshing engagement with a similar worm 49 keyed to the extended end of one of the mixing shafts 36.

The bottom of the mixing chamber 10 is provided with an opening or aperture 50 for each unit, which will presently be described, and at opposite ends with openings which 0 communicate with vertical conduits 51 arranged at opposite ends of the machine. The openings in the bottom of the mixing chamber are controlled by sliding valve plates 52 which slide across the openings and are extended to one side of the machine. The valve plates are connected together and to a common nut 53 adapted for longitudinal movement along a screw shaft 54 having opposite ends journaled in brackets extending from 15 the side of the machine. The outer end of the screw shaft is provided with a beveled gear 55 for engagement with a smaller gear 56 mounted upon a shaft 57. This shaft is driven by a sprocket 58 mounted thereon and 20 a chain 59 engaging a sprocket 60. The last mentioned sprocket is keyed to a shaft 61 extending longitudinally of the machine, and directly beneath this shaft is mounted a similar shaft 62 it of course being understood 25 that any suitable means can be provided upon the shaft 57 whereby the valve plates may be controlled at the will of the operator.

As stated before, a plurality of units are provided in the machine illustrated herein 35 and as they all are identical in construction, a description of one will suffice for all. As clearly seen in Figures 3 and 5, the units are spaced apart for a purpose which will appear hereinafter. Each unit consists of upper and lower conduits 63 spaced vertically, the upper conduit being in communication 40 with the opening in the bottom of the mixing chamber, while the lower screw conduit communicates with a longitudinally extending conduit 64 which is of three different diameters as clearly seen in Figure 3 for a purpose 45 which will presently appear. As the units on one end of the machine are grouped together and the three on the opposite end are similarly grouped, a longitudinally extending 50 passage way 64 is provided for each three units of a group. A screw 65 extends longitudinally of each of the screw passages 63 and one end of the screw shaft upon which the 55 screw is mounted is journaled in a spider 66 as most clearly shown in Figure 12 arranged at the inner end of the screw passage 63, while the opposite end of the screw shaft is journaled in a head secured to the outer end 60 of the screw passage. The outer end of each screw shaft is extended beyond the head of the passage and is equipped with a clutch mechanism. This mechanism consists of a clutch member 67 slidably mounted upon the 65 end of each shaft and a clutch member car-

ried by a beveled gear 68 loosely mounted upon the free end of each screw shaft. These beveled gears 68 are adapted for meshing engagement with the beveled gears 60 mounted upon the longitudinally extending shafts 61 70 and 62 and in this way rotary movement is imparted from these shafts to the screws 65.

As clearly seen in Figure 1, each of the shafts 61 and 62 is provided with a sprocket wheel 69 over which passes a sprocket chain 70. An additional sprocket 71 is keyed to the lower shaft 62 and a chain 72 engaging therewith also engages a sprocket 73 keyed to the driven shaft 25 as clearly shown in Figure 5.

The chamber in which the active material is applied and affixed to the grids is indicated in its entirety by the numeral 74 and forms a part of each unit. This chamber is provided by equipping the outlet end of each screw passage 63 with an enlarged arcuated shell 75, the end thereof adjacent the screw being substantially circular, and the opposite end thereof is open. As clearly seen in Figure 2, the open ends of these two shells 90 face toward each other and are slightly spaced apart so that grids may readily pass horizontally therebetween. It is to be particularly noted that the outer edge 76 of each open end of the shell is outwardly flared 95 to facilitate entrance of the grids into the casing and to provide a cam surface for a purpose to be later disclosed.

A shaft 77 is journaled through the upper shells 75 to extend longitudinally of the machine, and a similar shaft is journaled through all of the lower shells, it being noted that these two shafts are in the same vertical plane. The purpose of these shafts is to impart oscillatory movement to the two plungers 78 mounted in the shells. The outer ends of the shafts 77 are extended beyond their bearings and the extended ends of the lower shaft are each provided with a gear 79 having teeth one quarter of the way around its periphery. The extended ends of the upper shaft 77 are each provided with a similar gear 79 having a lever 80 extended therefrom and formed integral therewith. One end of a rod 81 is pivotally connected to the free end of the lever 80, while the opposite end is provided with a yieldable connection 82 for engagement with one end of a forked lever 83. This lever is pivotally mounted between its ends and its free end is bifurcated as at 84, a pin 85 of a lever 86 being adapted for movement in the bifurcation to rock the forked lever and consequently oscillate the two shafts 77. The crank arm 86 is secured to a gear 87 fixed upon the extended end of a screw shaft 88 mounted for rotation longitudinally in the screw passage 64, as most clearly seen in Figure 4. It will of course be understood that a similar screw shaft is mounted within the other longitudinally ex- 130

tending screw passage 64, as clearly seen in Figure 3, the extended end of this shaft being provided with a gear 84'. It will also be noted that each screw shaft 88 is of three 5 different diameters to fit the various diameters of screw passage 64, whereby an equal amount of active material will be fed to all three lower screws of this respective group. A sprocket 89 is keyed to the extended end 10 of each screw shaft 88 whereby rotary movement may be imparted to the screw shaft through the intermediacy of a sprocket 90 secured to the driven shaft 25 and a sprocket chain 91 on one end of the machine and a 15 sprocket 92 clutched to the shaft 32 driving a sprocket chain 93.

Rotary movement of the sprocket 87 is obtained through the medium of a segmental gear 94 having teeth at opposite points upon 20 its periphery whereby the gear 84' and sprocket 87 will be intermittently driven and consequently the lever 33 will have an interrupted oscillatory movement. A sprocket 95 is secured to the gear 94 and a sprocket chain 25 96 engages over this sprocket and a sprocket 97 keyed to the driven shaft 25.

In order that the plungers 78 may transfer the active material from one side thereof to the other, the plungers are mounted 30 upon sectional shafts 98. These shafts are arranged above and below the shafts 77 and are in the same vertical plane therewith as clearly seen in Figure 7. Referring more 35 particularly to Figures 7, 8, 9, 10, 11, 13 and 14, and more particularly to Figure 8, it will be seen that the sections 99 of the shafts 98 have mounted thereon the plungers 78 and that the free ends of the swinging sections 99 operate in arcuate slots 100 provided in opposite sides of each shell 75. The ends of 40 each swinging section 99 are each provided with a diametrically extending rib 101 adapted for reception within a similarly arranged groove 102 in each end of female member 103. These members are secured to the ends 45 of the sections 99 by screws 104 extending longitudinally through the female members and the movable sections so in reality the female members form integral parts of sections 50 99. These female members 103 are circular in cross section in which the groove 102 is provided and one end of this circular portion is provided with an enlarged head portion 104 in the end of which is provided a diametrically extending groove 105. As most clearly 55 seen in Figure 8, these female members 103 are disposed outside of the shells 75 and the circular portions of cooperating female members are mounted within the eyelet ends 106 of a pair of arms 107 forming a part of a 60 link member 108 which is secured to its adjacent shafts 77. It will therefore be obvious that the plungers may swing in an arc of a circle when the shafts 77 are actuated. 65 However, in order that the shafts 98 may

also rotate as a whole, a male section 108 is positioned between each pair of swinging sections 99. Each male section consists of a hub portion 109 having an enlargement 110 at each end thereof. A diametrically extending rib 111 is provided upon the end of each enlargement 110 for cooperation with the groove 105 in the female members. The male members are mounted for rotation by hangers 112 engaging the axle portions 109 of the male members. Each hanger has its bearing portion constructed into a pair of sections one of which 113 is resiliently held in cooperation with its coacting section. This is accomplished by extending screws through 80 the section 113 and threading them into the remaining section and providing springs 114 for engagement with the movable section so as to normally urge the same into engagement with its coacting section. Consequently, it will be manifest that when the male member is turned by movement of the plunger and is disengaged from its female members, it will remain in a position to be properly engaged by the female members when the plungers 90 return to their normal positions. From the foregoing, it will be obvious that when the shaft 98 rotates, all sections thereof will rotate when the plungers 78 are disposed in the position shown in Figure 7. However, when the shaft 77 is actuated to oscillate a plunger, the female members 103 will become disengaged from the male member, thereby permitting free swinging movement of the plungers. However, when they return to their normal positions in the end of the pasting chamber, it will be seen that the tongues 111 of the male members will be received in the grooves 105 of the female members so that all sections of the shaft 98 will 105 rotate when the latter is actuated. The opposite flat faces of the two plungers are equipped with grooves 115 corresponding in design to the net work of bars of the grids fed into the machine so that the plungers 110 may force the active material between the net work of bars without damaging the latter.

The shafts 98 receive rotary motion from sprockets 116 keyed to the extended ends of the shafts which are extended beyond the 115 units and a sprocket chain 117 engages the sprockets. A Geneva wheel or Geneva stop 118 is secured to the extended end of the upper shaft 98 and spaced pins 119 carried by a disk 120 cooperate with the slots in the 120 Geneva wheel for intermittently rotating the shaft 98. A sprocket 121 is keyed to the shaft upon which the disk 120 is secured and receives motion from the driven shaft 25 through the medium of a sprocket wheel 122 125 keyed thereto and a sprocket chain 123. A similar sprocket 121 and disk 120 for cooperation with a Geneva wheel 118 at the opposite end of the machine receives power through the medium of a sprocket chain 124 130

riding over a sprocket 125 keyed to the opposite end of the driven shaft 25, as clearly seen in Figure 6.

In order to provide an endless conveyor for 5 the machine and for delivering the grids to a position between the plungers, the sprocket shaft 126 similar to the shaft 32 is mounted longitudinally of the machine and in the same plane with the sprocket shaft 32. In view of 10 the fact that I contemplate a separate conveyor for each unit, pairs of spaced relatively large sprockets 127 are keyed at spaced intervals along both shafts 32 and 126, the corresponding pairs on the two shafts being adapted 15 for engagement with a pair of endless sprocket chains 128 of standard make. It will be noted that the two chains 128 comprising a single endless conveyor are spaced apart a distance whereby the chains are arranged 20 beyond opposite sides of its respective unit. By referring more particularly to Figures 28, 29, 30 and 31 it will be seen that pivot pins 129 at spaced intervals along the chains 128 are extended a substantial distance inwardly 25 of the respective chain to receive thereon bed links 130. Each bed link consists of a U-shaped member, the arms of which are received upon the pivot pin 129, it being noted that one of the arms 131 is considerably nar- 30 rrower than its coacting arm so that the extensions 132 of the double grids 133 will engage therewith and be carried along with the conveyor chain. In order that the extensions from the grids will be securely retained in engagement with the bed links 130, a master link 134 is pivoted between its ends and between the arms of the bed link upon the pivot pin 129. The end of this link which overlies the bed link is equipped on its 35 lower edge with squared depending nose 135 adapted for engagement with the upper surface of an extension of a grid. This end of the link is also provided with a track engaging roller 136, while the opposite end 40 of the link is equipped with a trundle roller 137.

The lower part of each upper shell 75 is provided with laterally projecting tracks 138 on opposite sides thereof, which are adapted 50 to engage the rollers 136 of the master links and force the latter downwardly so that the squared noses 135 rest upon the grid extensions 132 and clamp the same to the conveyor whereby accidental displacement of the grids 55 is prevented, while they are undergoing the pasting operation.

The means for smoothing and removing surplus active material from the grids after they have been pasted by the plungers, consists of a pair of spring pressed opposed plates 139 disposed a distance to the rear of each unit; a pair of the plates being provided for each unit. These plates are slidably engaged with a pair of spaced bars 140, and are 60 normally urged together by coiled springs

141 engaging the plates and brackets 142 fastened above and below the plates. These plates are arranged between the chains of each endless conveyor 128 and during operation of the machine it will be obvious that 70 the grids are pulled between the smoothing plates 139 so that they will be finished off properly and all surplus material removed therefrom.

The inner edges of the plates flare and any 75 surplus material gathered from the grids will slide upon the lower flared end onto a slide 143 suitably positioned to catch the material as it drops from the smoothing plates. From the slide, the surplus material is delivered 80 onto an endless apron 144 extending longitudinally of the machine and engaged around rollers 145, one of which is mounted upon a stub shaft 146 carrying a sprocket 147. This sprocket is driven by a sprocket chain 148 85 engaging over a sprocket 149 mounted upon the extended end of the shaft 19. The other roller of the endless apron is mounted upon the shaft 150 carrying a sprocket 151. The sprocket 151 is carried on the shaft 150 which 90 is driven by a chain connection from the sprocket 159 through the bevel gears 20 and 21.

Surplus material from the apron 144 is delivered to a vertically arranged endless conveyor 152 by a chute arrangement 153, as 95 clearly shown in Figure 6. This conveyor consists of a double vertical tube 154 in which operates an endless cable 155 having secured thereon at spaced intervals, disks 156 which 100 are disposed horizontally when passing through the tubes 154. Sheaves 157 are mounted upon shafts 158 above and below the tube so that the cable 155 may be received in the grooves of the sheaves and moved in 105 the desired manner. The lower shaft 158 is extended and equipped with a sprocket 159 whereby a sprocket chain 160 may transmit movement between the conveyor sprocket 151 to the shaft 158. Adjacent the top of the 110 conveyor, a chute 161 is provided and inclines downwardly to enter the mixing chamber 10, whereby all surplus material from the conveyor 152 is conveyed back into the 115 mixing chamber.

The means for delivering the grids to the 120 endless conveyor and chain 128 consists essentially of an inclined screw 162 mounted for rotation in bearings 163 carried by a forwardly extending bracket 164 secured to the base of the machine. A screw drive shaft 165 is similarly mounted in the bracket 164, the upper end of the shaft being provided with a beveled gear 166 adapted for meshing engagement with a similar gear 167 loosely 125 mounted upon the shaft 126. As clearly seen in Figure 24, this beveled gear 167 is provided with a clutch member 168 adapted for cooperation with a clutch member 169 slidably mounted upon the shaft 126 and pro- 130

vided with an operating member 170 encircling the clutch operating member and pivotally supported by the bracket 164. The clutch operating member 170 is provided 5 with a cam engaging roller 171 for engagement with a part to be hereinafter described whereby the clutch may be automatically operated. The lower end of both the screw 162 and screw drive shaft 165 are extended be- 10 yond the lower end of the bracket 164 and are equipped with meshing gears 173 whereby power from the shaft 165 is transmitted to the screw 162.

As best seen in Figures 17 and 18, the bearings 163 are connected by an inclined track 174 to opposite edges of which adjacent the top thereof are secured spring catches 175. The noses of the catches engage over the free ends of the retaining bars 176 pivoted at 20 their lower ends as at 177 to the track 174. A retaining bar 176 is pivoted to each longitudinal end of the track 174 and when disposed in a closed position as shown in Figure 17, slots 178 in opposite sides of the mechanism are provided for the reception of the lateral extensions 132 of the grids whereby they will be properly maintained upon the feeding mechanism in positions to be delivered to the endless chain 128.

30 As best seen in Figures 15 and 16, a feed member 179 of the grid feeding mechanism consists of a nut member comprising a pair of jaws pivoted between their ends as at 181, whereby a bolt 182 may be pivotally connected to the free end of one jaw and threaded through the other jaw. A coiled spring 183 is positioned upon the bolt between the free ends of the jaws to normally urge the screw engaging ends of the jaws into engagement 35 with the screw 162. This construction is provided for so that the feed member 179 may be returned to the bottom of the mechanism after the entire supply of grids has been advanced to the endless chain. The screw is 40 provided with a table 184 which is equipped at opposite edges with lateral extensions 185 adapted to ride in the slots 178 provided by the retaining bars 176. As it will be remembered that the endless chain 128 moves intermittently through the intermediacy of the 45 geneva 33, it will be appreciated that the screw 162 through the intermediacy of the shafts 126 and 165, will also be driven intermittently and consequently the feed member 50 179 will also be advanced intermittently and in proportion to the speed of the endless chain so that the grids upon the feed member will be in proper position to be engaged by the 55 endless chain.

60 It will of course be understood that I provide a feeding mechanism for each unit and in order to automatically stop any one of the feed mechanisms and paste feeding means for any one of the units when the supply of grids 65 in the feeding mechanism has been exhausted,

I equip the machine with an automatic stop mechanism for accomplishing these functions. This stop mechanism embodies a depending portion 186 on the feed member 179, as clearly shown in Figures 20 and 21, this portion being equipped with a cam member 187 adapted for engagement with the cam engaging roller 171 of the clutch operating member 170 when the feed member reaches the limit of upward movement upon the screw 75 162. When the cam engages the clutch operating member 170, the latter is caused to swing upon its pivot and disengage the clutch member 169 from the coacting clutch member 168 so as to stop rotation of the screw shaft 80 162. At the same time, the clutch operating member 170 throws the clutch out, it also slides a member 187' upon the shaft 126 so that a laterally extending pin 188 carried by this member is arranged in a position to engage a depending shoulder 189 of a bar 190 to move the same longitudinally during rotation of the member 187'. This member is splined upon the shaft 126 so that it may rotate therewith and slide longitudinally thereupon when engaged by the clutch operating member 170. As a similar stop mechanism is provided for each feed mechanism and its coacting paste feeding means, a description of 85 one will suffice for all. The bars 190 are arranged in a horizontal plane, one end of each lever being supported in proper position above the shaft 126, as clearly seen in Figure 26, by a laterally extending pin 191 carried by a bracket 192 engaging in a longitudinally extending slot 193 in the adjacent end of the bar 190. The opposite end of each bar is pivotally connected as at 194 to a shaft operating lever 195 carried by one of the shafts 196 which will presently be described. 90

In the present six unit type of machine as illustrated, a lever shaft 197 is mounted longitudinally in the rear of the clutch shaft 126, one lever shaft being provided for each three units. The tubular shaft 196, carrying a lever 195 which is connected to the bar 190, is rotatably mounted upon a second tubular shaft 198 which in turn is rotatably mounted upon the lever shaft 197. Each of these shafts 196, 197 and 198 is provided with a lever 195, 115 it being understood that a shaft is provided for each unit of the group of three. A second lever 199 is formed integral with the lever 195 and extends in the opposite direction and is pivotally connected as at 200 to a rod 201. 120 The opposite end of this rod is pivotally connected to the lower end of a clutch operating lever or member 202 which is pivotally supported as at 203 above the lower feed screw clutch 67 and in the rear of the head which 125 closes the rear end of the screw passage 63. This lever is equipped with clutch engaging arms 204 so that the clutch member 67 may be operated thereby.

In order that the upper feed screw 65 may 130

be simultaneously stopped with the lower feed screw, each of the shafts 196, 197 and 198 are also provided with a lever 205 connected to one end of a connecting rod 206 disposed vertically of the machine and pivotally connected to one arm of a bell-crank lever 207 mounted upon a horizontally disposed shaft 208 arranged above the pasting chamber. A second connecting rod 209 is pivotally connected to the other end of the bell-crank lever 207 and to a clutch operating lever 208 similar in construction to the clutch lever 202 for the lower screw 65 and is mounted in the same manner, whereby the clutch of the upper screw may be operated.

From the foregoing, it will be seen that when any bar 190 is moved longitudinally through the intermediacy of the grid feeding mechanism, the levers 199 and 205 will be swung to throw out the clutches of the feed screws 65, thereby preventing the active material being forced into the pasting chamber when the supply of grids upon the feeding mechanism has been exhausted.

In order that the cam engaging rollers 136 as clearly shown in Figure 30 may properly engage the pasting chamber whereby the master link 134 may be caused to clamp the grids upon the endless conveyor chain 128, a cam platform 211 is secured in a horizontal position to the upper end of the grid feeding mechanism or more particularly to the uppermost bearing 163. As clearly shown in Figure 17, the forward end 212 of this platform is slightly inclined so as to engage with the rollers 137 of the master links so as to tilt the same, whereby the cam engaging rollers 136 of the links will be thrown into engagement with the cam plate 138. As clearly shown in Figure 31, the platforms 211 for the intermediate units are provided with a double track 213, one track forming a runway for one side of one endless conveyor, 128, while the other track forms a run-way for one side of the adjacent conveyor. It will of course be seen that the cam plates 138 are secured by means of screws 214 to an upstanding portion 215 of the platform 211, it being noted that the upstanding portion 215 is extended above the track 214, whereby the cam plate 138 is arranged in spaced relation to the platform. The operation of the machine is as follows: The grid feeding mechanism being intermittently operated and adapted to advance the uppermost grid carried upon the platform 179 of the feed member to a position whereby the extensions 132 of the uppermost grid may be engaged by the bed links 131, it is timed so that the uppermost grid on the track arranged in the feeding mechanism is always in position to be engaged by the bed links 130 as they reach the relative top of the sprocket 127. As stated before, the master links 134 clamp the said extensions upon the bed links and when the intermittently oper-

ated conveyor chain 128 is advanced, a grid is advanced to a position between the pasting shells in the path of movement of the oppositely acting plungers 78, at which time the endless conveyor is brought to a stop. During this operation the material has been fed by the screws 65 through the spiders 66 and is evenly distributed upon the plungers 78. Through the intermediacy of the mechanism heretofore described, the plungers carry with them the paste which has been distributed thereupon so that the active material is disposed upon the faces of the plunger remote from the feed screw 65. Immediately after the plungers have completed this operation, the shafts 77 are oscillated through the medium of the forked lever 83 whereby the plungers are swung toward each other to apply the active material carried thereby to opposite faces of the grid arranged in the pasting chamber. The space between the two plungers when they reach the extent of their oscillatory movement is less than the thickness of the grid and consequently the active material is forced compactly between the interlaced bars of the grid.

As soon as this operation has been completed, the endless conveyor 128 advances again to align another grid with the plungers. After this operation has been carried out two or three times, the first grid pasted is then passed between the spring pressed finishing plates 139 where the active material is smoothed upon the grid and all of the surplus active material deposited thereon is scraped off and delivered through the intermediacy of the slide 143 to the endless apron 144. The surplus active material is then conveyed back to the mixing chamber in the manner as set forth previously. When the pasted grids have reached the sprockets 127 in the rear of the machine, the master links release the grids whereby they may pass down a slide 216 to any suitable location.

The foregoing description and the accompanying drawings have reference to the preferred or approved embodiment of my invention. It is to be understood however, that such changes may be made in construction and arrangement of parts, materials, dimensions, etc. as may prove expedient and fall within the scope of the appended claims.

Having thus fully described my invention what I claim as new and desire to secure by Letters Patent is:—

1. In a grid pasting machine opposed plungers movable in an arc and being rotatable at one point in their travel to transfer material from location on one side of the axis of each plunger to the other side thereof.
2. In a grid pasting machine, a plunger chamber, a plunger movable therein, said plunger being reversible whereby the face thereof adjacent one end of the chamber and which receives active material will be dis-

posed to face the opposite end of the chamber when the plunger is started to its paste applying position.

3. In a grid pasting machine, a pasting chamber, paste feeding means at opposite ends thereof, opposed plungers mounted in said chamber for swinging movement and said plungers also being rotatable whereby the faces of the plungers adjacent the paste feeding means will be turned to face each other at the beginning of their swinging movement.

4. In a device of the class described, a plurality of pasting chambers, upper and lower paste conduits communicating with opposite ends of each chamber, a feed screw in each conduit, a mixing chamber communicating directly with the upper conduit, passageways at the ends of said mixing chamber, auxiliary conduits communicating with the passageways and the lower conduits, and means therein for conveying paste to the lower conduits.

5. In a device of the class described, the combination with paste feeding means, clutch means associated therewith, of a grid feeding mechanism including a feed member, stop means at the limit of movement of the feed member, and means connecting said stop means and clutch means for operating the latter when the feed member reaches the limit of its movement.

6. In a device of the class described, the combination with paste feeding means, of a grid feeding mechanism including a feed member, a clutch mechanism for controlling said paste feeding mechanism and actuated by said feed member to stop the grid feeding mechanism and the paste feeding mechanism when the feed member reaches the limit of its movement.

7. In a device of the class described, paste feeding means, a clutch mechanism for controlling the same, of a grid feeding mechanism including a feed member, and a driving shaft, a sliding member on said shaft, connections between said sliding member and said clutch mechanism, and said feed member adapted to actuate the sliding member upon reaching the limit of its movement for stopping the paste feeding mechanism and the grid feeding mechanism.

8. In a device of the class described, the combination with means for applying active material to storage battery grids, of an endless conveyor, means for feeding the grids thereto and means carried by the conveyor for releasably securing the grids thereto.

9. In a device of the class described, the combination with means for applying active material to storage battery grids including a passage, of an endless conveyor, and means carried by the conveyor and engaging the walls of said passage for releasably gripping the grids.

10. In a device of the class described, a sec-

tional shaft, a plunger mounted for rotation upon each section of said shaft, a second shaft for oscillating the plungers, and means connecting the sections of said first named shaft with the second shaft, whereby oscillation of the second shaft will oscillate all of the plungers.

11. In a device of the class described, a shaft having a displaceable section rotatable with the shaft, said section having its ends provided with grooves, a plunger secured to said shaft, said shaft capable of swinging movement as a whole while the sections thereof remain relatively stationary and having grooves for cooperation with the tongues of said sections, whereby said section may rotate with the shaft when in alignment therewith, and a second shaft for oscillating the plunger.

12. In a device of the class described, a pair of intermittently operated shafts, opposed plungers mounted thereon, a second pair of shafts between the first pair, connections between the second shafts and plungers, segmental meshing gears on said second shafts, a crank on one of said gears, a forked lever having connection with said crank, and a second crank having a pin operated in the forked end of said lever for rocking the same and oscillating the plungers.

13. A grid pasting machine comprising a plunger chamber, a plunger operable therein, means communicating with one end of the chamber for feeding active material thereto, and said plunger being reversible whereby the face thereof adjacent one end of the chamber and which receives the active material will be disposed to face the opposite end of the chamber when the plunger is moved to a paste applying position.

14. A grid pasting machine comprising a plunger chamber, a rotary and swinging plunger arranged therein, active material feeding means communicating with one end of said chamber for feeding active material to a face of the plunger, and said plunger being reversible whereby the face thereof which receives active material will be disposed at the opposite side of the plunger when the latter is disposed in a paste applying position.

15. A grid pasting machine comprising a plunger chamber, a plunger therein, means for supplying plastic active material to one end of the chamber, a rotary shaft journaled through one end of the chamber adjacent the means for supplying active material thereto, said shaft including a removable section on which is mounted the plunger, and means for swinging said plunger section of the shaft after the latter has been turned to reverse the position of the plunger whereby the active material deposited thereon will be disposed in a position to be pressed into the grids.

16. A grid pasting machine comprising a plunger chamber having its ends spaced apart to provide an admission point for grids to be

pasted, a rotatable and swinging piston arranged in each chamber and adapted to move toward the grid passed between the chambers, and active material feeding means for supplying active material to the ends of said chambers remote from the point of admission of the grids.

17. A grid pasting machine including a shaft consisting of a rotating male section, and a pair of rotating and swinging female sections, said male and female sections adapted to rotate in unison when they are disposed in longitudinal alignment, and the female sections being movable out of longitudinal alignment with the male section.

18. A grid pasting machine including a plunger chamber, active material feeding means communicating with one end of the chamber, means spaced from said end of the chamber for distributing the active material entering said chamber, and a plunger mounted in the chamber and adapted to receive the active material evenly distributed by aforesaid means.

19. A grid pasting machine including a pair of spaced sectional shafts, sections of said shafts being movable in an arc of a circle, a plunger mounted on each of said movable sections, said sectional shafts being intermittently rotated and a pair of intermittently operated rotatable shafts arranged between said sectional shafts and connections between said last named shafts and the movable sections of the first named shaft whereby the plungers are caused to move toward each other upon rotation of said second mentioned shafts.

20. A grid pasting machine including a grid pasting mechanism comprising a pair of spaced chambers between which grids are automatically fed, to conveyor means for automatically delivering and discharging grids to the grid pasting mechanism, pivoted means carried by said conveyor for engagement with the grids, and means co-operating with the pivoted means for causing them to grip the grids while the active material is being applied thereto and for releasing the same when they are to be discharged from the conveyor.

21. A grid pasting machine including a pasting mechanism, an endless conveyor for delivering grids thereto, a feeding device operable to automatically deliver grids to a position to be carried off by the endless conveyor, links depending from the conveyor for engaging the grids and carrying them from the feeding device to the paste applying mechanism, and means carried by the said links for temporarily fastening the grids thereto whereby they will be held steady during the paste applying operation.

22. A grid pasting device comprising in combination a paste applying mechanism, and paste feeding means for furnishing the apply-

ing mechanism with paste, a grid feeding device, means for delivering grids from the feeding device to the paste applying mechanism, said feeding device including a follower, a rotating shaft for operating the follower, an operative connection between the shaft and the follower, clutch means carried by the shaft, said clutch being engageable by the follower whereby the clutch is operated, clutch means for controlling the movement of the paste feeding means, and levers connecting the clutches of the said shaft and paste feeding means whereby the latter is rendered inoperative and means whereby the operation of the follower disengages the clutch of said shaft.

23. A grid pasting machine comprising in combination, a paste applying mechanism, means for feeding paste thereto, a grid feeding device including a follower, a conveyor leading from said feeding device and having a receiving end arranged to automatically receive grids from said device, a shaft for moving the follower, an operative connection between the follower and the shaft, a clutch on said shaft and including a pin extending parallel to said shaft, clutch means for the paste feeding means, a reciprocatory link having a shoulder engageable by said pin when the clutch of the follower driving shaft is moved by engagement with the follower, means connecting said reciprocatory member to the clutch means of the paste feeding means whereby the paste feeding means is automatically stopped when the follower is moved to the extent of its movement and means for actuating said follower.

24. In a grid pasting machine, means for applying paste to the grids, a grid feeding device including an inclined track upon which the grids are adapted to move, the sides of the track being arranged to receive and guide lug extensions of the grids, a follower movable longitudinally of the track, means for intermittently moving the follower to cause an intermittent movement of said grids to the delivery end of the track, and a conveyor leading from said delivery end to the means for applying paste thereto.

25. A grid pasting machine including a paste applying mechanism, an endless conveyor for delivering grids having lateral lugs thereto, a feeding device having a delivery end arranged to automatically deliver grids to the conveyor, links carried by the conveyor and including portions for supporting the lugs of the grids, a track cooperating with the endless conveyor for assisting in supporting the grids carried by the conveyor, and automatically operable means for clamping the lugs to the supporting portions of the links.

26. A grid pasting machine comprising in combination means for applying paste to the grids, means for feeding paste to the paste

applying means, a grid feeding device, means for conveying grids from the feeding device to the paste applying mechanism, said feeding device being arranged in advance of the 5 endless conveyor and having a delivery end arranged to automatically deliver grids to the conveyor, and means cooperating with the

feeding device and the paste feeding means whereby the latter is automatically thrown out of operation when the supply of grids in 10 the feeding device has been exhausted.

In testimony whereof I affix my signature.

HENRY J. MCKENZIE.
